UNITED STATES PATENT OFFICE.

GEORGE W. SPALDING, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

WOVEN POCKETED CARRIER.

1,338,795.

Specification of Letters Patent.

Patented May 4, 1920.

Application filed August 18, 1917. Serial No. 186,888.

To all whom it may concern:

Be it known that I, GEORGE W. SPALDING, a citizen of the United States, residing at Worcester, in the county of Worcester, State 5 of Massachusetts, have invented a certain new and useful Improvement in Woven Pocketed Carriers, of which the following is a specification, reference being had therein to the accompanying drawings.

10 The invention has relation more particularly to the internal reinforcements with which the pockets of woven carriers are furnished in some cases. Such reinforcements are combined with the pockets of cartridge 15 carriers, for instance, to reinforce the walls and bottoms of such pockets against wear and injury from the sharp points of the bullets of cartridges and the corners of cartridge clips placed in such pockets.

20 The general object of the invention is to provide an internal reinforcement of practical character affording complete and effective protection, especially to the side-walls of a pocket.

25 The drawings show an illustrative embodiment of the invention.

In the drawings,—

Figure 1 is a perspective view of a portion of a pocketed carrier, comprising two adjacent joining pockets.

30 Fig. 2 is a view of one of the pockets in horizontal section on line 2, 2, of Fig. 3.

Fig. 3 is a view of the said pocket in vertical section.

35 Fig. 4 is a front view of a combination flap or cover-piece and reinforcement-lining made in accordance with the invention, with its upper end left in an unfinished state.

40 Fig. 5 is a back view thereof.

Fig. 6 is an edge view thereof.

Fig. 7 is a diagram illustrating the manner in which combination flap or cover-pieces and reinforcement-linings like that of

45 Figs. 4, 5 and 6 are produced as consecutive portions of a continuous woven web.

Fig. 8 is a view showing separately a blank for one of the said combination linings, produced by cutting the web of Fig. 7 into its component portions or blanks.

50 Fig. 9 shows the blank of Fig. 8 with one end margin of the same turned or folded back upon the adjoining portion of the

blank, for the purpose of providing the lining with a smooth and finished top edge. 55

Figs. 7, 8 and 9 are on a smaller scale than the other views of the drawings.

The carrier of Figs. 1, 2 and 3 is of the well-known type in which a plurality of pockets and a supporting-band or body are 60 woven integral with one another, each pocket having the back-wall 1 thereof, front-wall 2, side-walls 3, 3, and bottom 4, woven in well-known manner to produce the required pouch-like formation. 5, 5, are 65 connecting web-portions between pockets. In practice, reinforcement-linings embodying the invention are applicable to carrier-pockets of a variety of forms and constructions. The specific character of the pockets 70 to which the improved reinforcement-lining is applied is not material.

The improved reinforcement-lining consists in a strip which, in addition to being bent into U-shape as represented in Figs. 3, 75 4, 5 and 6, so as to line the back and front-walls and bottom of the pockets to which it is applied, has one upright portion thereof furnished with oppositely projecting lateral wings *c*, *c*, which line the sides of the pocket. 80 The said upright portion may be either the back upright portion *a*, or the front upright portion *b*, but preferably is the front portion *b*. These wings *c*, *c*, fold around the side-margins of the opposite upright portion, in this case the back upright portion *a*, as shown in Figs. 2, 4, 5 and 6, and their ends are secured thereto by vertical lines of 85 stitches *a*³, *a*³, Fig. 5. The said ends of the wings intervene between the said upright portion of the lining and the corresponding wall of the pocket, as shown in Fig. 2.

The different portions *a*, *b*, *c*, *c*, of the lining are secured to the back-wall, front-wall, and side-walls, of the pocket, in suitable manner and by suitable means, as, for instance, by lines of stitches 8, 8, forming stitched seams. 95

Preferably, though not necessarily in all cases, the back portion *a* of the lining is extended upward in a continuation *a'* which is made into a cover or flap. The cover or flap of one of the pockets in Fig. 1 is shown in straight and extended or open condition, that of the other pocket in such figure 100 being shown folded down over the pocket 105

and fastened in closed condition by means of its fastening devices 6, 7.

Reinforcement-linings such as that which has been described may be produced by weaving a continuous web like that shown in Fig. 7, namely, comprising a succession of portions adapted to be separated into T-shaped blanks like that shown separately in Fig. 8, by cutting across the said web transversely at suitable intervals. The said web as shown in Fig. 7 comprises successive narrow portions a^x constituting the narrow portions or stems of successive blanks, and intervening wide portions a^y constituting the wide portions or heads of the said blanks. In order to shorten the view, parts of the length of one narrow portion are broken out. Preferably, each narrow portion of the said web is of a length suitable to constitute the narrow portions or stems of two successive blanks, arranged end to end with relation to each other, and each wide portion thereof is of a length suitable to constitute the wide portions or heads of two successive blanks. The cutting of the web into blanks is effected on lines, x , x , and y , y , Fig. 7, at mid-length of the narrow portions and wide portions, respectively, of the web. In the web of Fig. 7 the portions which subsequently constitute individual blanks are alternately reversed relative to one another.

In weaving the web of Fig. 7 the warp-threads z , z , which are used in the production of the laterally projecting parts of the wide portions of the web are floated alongside the narrow portions of the said web from one wide portion to the next, and are trimmed off adjacent the said wide portions subsequent to the weaving, in finishing the blanks. As produced, the latter have selvage edges at both sides of the narrow portions or stems and also at the outer extremities of the wings of the wide portions or heads thereof.

The terminal edge of the wide portion a^y of a blank is turned or folded upon itself, as at a^2 , Fig. 9, to give a smooth and

finished turned edge to the top of the lining. See also Figs. 3 to 6. When the blank is bent into U-shape as in Figs. 3 to 6, the turn or fold a^2 is caused to come at the outside of the lining so that when the latter is placed within a pocket the turned-down raw edge will be located next the inner surfaces of the pocket-walls and be covered and hidden.

What is claimed as the invention is:—

1. The combination with a carrier-pocket, of a reinforcement-lining comprising a strip bent into U-shape so as to line the back and front-walls and bottom of said pocket, and also having one upright portion thereof furnished with oppositely-projecting lateral wings which line the sides of the pocket, are folded around the opposite upright portion, and are secured in place between the latter and the corresponding wall of the pocket, said reinforcement-lining having the top margin of the said upright portion and its wings doubled back upon itself to produce a smooth and finished turned top edge.

2. The combination with a carrier-pocket, of a combined flap or cover and reinforcement-piece comprising a strip having its lower portion disposed within the pocket as a reinforce for the back of the pocket and also bent into U-shape so as to line the bottom and front of the pocket, and having the upright front portion provided with lateral wings projecting oppositely therefrom, lining the sides of the pocket, folded around the edges of the back-reinforcement, and secured in place between the latter and the corresponding wall of the pocket, said reinforcement-lining having the top margin of the upright portion and its wings doubled back upon itself to produce a smooth and finished turned top edge.

In testimony whereof I affix my signature in presence of two witnesses.

GEORGE W. SPALDING.

Witnesses:

WILLIAM BRADFORD,
HAZEL MALMSTEDT.
